UNITED STATES PATENT OFFICE.

BENJAMIN W. TUCKER, OF NEWARK, NEW JERSEY, ASSIGNOR TO THE MARLES CARVED MOULDING COMPANY, OF PHILADELPHIA, PENNSYLVANIA, A CORPORATION OF WEST VIRGINIA.

CARVING-MACHINE.

SPECIFICATION forming part of Letters Patent No. 784,714, dated March 14, 1905.

Application filed April 1, 1902. Serial No. 100,904.

To all whom it may concern:

Be it known that I, BENJAMIN W. TUCKER, a citizen of the United States, residing in Newark, in the county of Essex and State of New Jersey, have invented certain new and useful Improvements in Carving-Machines, of which the following is a specification.

This invention relates to machines for carving repeat ornaments or a repeating series of ornamental characters in diaper on wood, moldings, or the like where two or more cutting members or sets of members, one or more for incising the contour of the ornament or a part thereof and another or others for making one or more angular cuts meeting said incision or incisions, coact to carve the desired design.

My invention consists in improved mechanism for actuating the cutters at a high speed to incise the desired design upon a continuously-moving stock, in improved mechanism, in combination with the cutters, for rendering the angle of incision thereof adjustable, in improved mechanism for imparting motion to the cutters and to the stock, and improved structure, combination, and organization whereby the objects of this invention may be carried out in an automatic machine.

The objects of this invention are to provide a machine for automatically and continuously feeding stock and incising thereon ornamental characters in a repeating design, to provide means for accomplishing this result in a series of steps continuously which will result in a finished product, and to provide adjustable and substitutive parts in said machine whereby stocks of various size and form may be accommodated and designs of varying pattern may be incised.

I have illustrated my invention embodied in a carving-machine in the accompanying drawings, in which like reference characters refer to like parts throughout the several figures.

Figure 1 is a side elevation; Fig. 2, a plan view; Fig. 3, a rear end view; Fig. 4, a vertical section on line $x-x$ of Fig. 2; Fig. 5, a vertical section on line $y-y$ of Fig. 2, showing stock-guide and counter-shaft carriage broken away; Fig. 6, a detail plan of a tool-carriage, tool-head, and tools thereon, showing diagram-

matically the movement of the tool-carriage 50 relative to the stock; and Fig. 7, an edge view of the tool-carriage and head with tools removed.

Referring to the drawings, the machine is supported upon a frame consisting of the two uprights A and B, maintained in their respective upright position by tie-rods 22. This frame has bearings 33 for supporting a continuously-revolving shaft 4, driven by pulley 5 or otherwise, for carrying the gear 6. The frame also has bearings 77 for supporting another continuously-revolving shaft, 8, carrying and driven by a gear 9, meshing with gear 6 and of equal diameter therewith.

The uprights A and B have upper portions 65 of relatively circular form and supporting members beneath. Each of the uprights A and B is apertured at approximately the center of its circular portion, and an angular stock-guide 10 is joined to said uprights in 70 alignment with the apertures therein. The stock-guide 10 is rectangular in cross-section and is secured to the frame in the position of the letter V. Upon the inner faces of the flanges of the stock-guide 10 are adjustably 75 secured plates 11 and 12, turned up into flanges 13 at their outer edges. Bolts 14, having flush heads countersunk in the plates 11 and 12 and provided with securing-nuts, are movable in transverse slots 15 in the flanges of the stock-guide 10. These plates 11 and 12 form means for conforming the stock-guide 10 to the different sizes of stock to be operated upon, and the turned-up flanges 13 of the plates 11 and 12 retain the stock within the stock-guide 85 throughout its entire length. This is a very necessary precaution in a machine of this character, as will be seen.

On the inner faces of the uprights A and B and adjacent the periphery of the circular portions thereof are fixed slide-rails 16, 16, describing perfect arcs of equal radius about a point lying at about the apex of the stock-guide 10. The slide-rails 16 are provided with T-slots 17 in their faces.

About the slide-rails 16 and concentric therewith are located racks 18, 18, securely bolted or otherwise secured to the uprights A and B.

Mounted between the rails 16 are counter-shaft carriages 19 and 20, slidably supported on said rails by guides 21 on their ends.

Each counter-shaft carriage 19 and 20 is provided with a shifter-shaft 22, mounted in journals 23 and 24 in said carriage. The shifter-shafts carry gears 25, meshing with the racks 18 and hand-wheels 26 at either or both ends. By rotating the shafts 22 by means of the hand-wheels 26 the gears 25 are caused to travel over the racks 18, and the counter-shaft carriages may be moved to any position upon the rails 16 independently of one another.

Bolts 27 are mounted in the end walls of each of the counter-shaft carriages opposite the T-slots 17 with their heads traveling within said slots, and the counter-shaft carriage may be rigidly secured in any position by tightening up on the nuts of said bolts on the inner side of their end walls.

As the counter-shaft carriages 19 and 20 slide upon rails 16 with fixed relation thereto, it will be seen that their angles of inclination to the stock-guide 10 is constantly changed as they are moved upon said rails.

Mounted, respectively, upon the counter-shaft carriages 19 and 20 in bearings 28 and 29 are counter-shafts 30 and 31, which have a constantly parallel relation to the shafts 4 and 8 with any position of the counter-shaft carriages 19 and 20.

The counter-shaft 30 carries and is driven by a gear 32. One end of a link 33 is journaled at 34 on the shaft 8 and at its other end is connected by a pivot-stud 35 to another link, 36, the opposite end of which link 36 is journaled to the counter-shaft 31 at 37. The shaft 8 carries a driving-gear 38. Two intermediate gears 39 and 40, mounted on studs 41 and 35 on the link 33, transmit motion from the gear 38 on shaft 8 to the gear 32 on counter-shaft 30 in the relation of two revolutions of the counter-shaft 30 to one of the shaft 8.

The train of gearing 38, 39, 40, and 32 transmit power from shaft 8 to counter-shaft 30, and the disposition of this train of gearing on the links 33 and 36 renders the train extensible and contractile and capable of lending itself to the varying space between the shafts 8 and 30, occasioned by the path of the counter-shaft carriage 20 not being concentric with the shaft 8.

The counter-shaft 31 carries and is driven by a gear 42. One end of a link 43 is journaled at 44 on the shaft 8 and at its other end is connected by a pivot-stud 45 to another link, 46, the opposite end of which link 46 is journaled to the counter-shaft 31 and 47.

Two intermediate gears 48 and 49, mounted on studs 50 and 45 on the link 43, transmit motion from gear 38 on the shaft 8 to the gear 42 on counter-shaft 31 in the relation of two revolutions of the counter-shaft 31 to one of the shaft 8.

65 The train of gearing 38, 48, 49, and 42 and

its disposition on the links 43 and 46 acts in the same manner and for the same purpose with reference to the counter-shaft 31 as the train of gearing 38 39 40 32 on links 33 and 36 acts with reference to counter-shaft 30. 7c Therefore it will be seen that the counter-shafts 30 and 31 revolve synchronously and are driven from and at double the speed of the shaft 8.

The shaft 4 is restricted against longitudinal movement by the abutment of the hubs of pulley 5 and gear 6 and a collar 51 with the bearings 3.

The links 33 and 43 are restricted against movement longitudinally of the shaft 8 by the hub of gear 38 and collars 52 and 53.

The links 36 and 46 are restricted against movement longitudinally of the counter-shafts 30 and 31 by the hubs of gears 32 and 42 and collars 54 and 55.

On the counter-shaft carriage 19 are mounted in bearings 56 and 57 parallel driven shafts 58 and 59, located beyond the ends of, perpendicular to, and in the same plane with counter-shaft 30. The shafts 58 and 59 are 90 inclined toward the median line of the machine at an angle to the path of the counter-shaft carriage 19, which angle may be varied to a certain extent when the machine is built to adapt it to any particular class of work and for purposes which will hereinafter appear.

The shafts 58 and 59 respectively carry and are driven by driven miter-gears 60 and 61, meshing with opposite sides of driving miter-gears 62 and 63 on the ends of counter-shaft 100 30, which arrangement acts to impart the motion of counter-shaft 30 to shafts 58 and 59 in the same direction and at equal speeds to that of counter-shaft 30.

The counter-shaft 30 is restricted against 105 longitudinal movement by the abutment of the hubs of the miter-gears 62 and 63 with the bearings 28 and 29.

The shafts 58 and 59 are restricted against longitudinal movement by the abutment of 110 the hubs of miter-gears 60 and 61 and collars 64 and 65 with the bearings 56 and 57.

On the counter-shaft carriage 20 are mounted in bearings 66 and 67 parallel driven shafts 68 and 69, located beyond the ends of, perpendicular to, and in the same plane with counter-shaft 31. The shafts 68 and 69 are inclined toward the median line of the machine at the same angle to the counter-shaft carriage 20 as the shafts 58 and 59 are to the counter-shaft carriage 19.

The shafts 68 and 69 respectively carry and are driven by driven miter-gears 70 and 71, meshing with opposite sides of driving miter-gears 72 and 73 on the ends of counter-shaft 31, 125 which arrangement acts to impart the motion of counter-shaft 31 to shafts 68 and 69 in the same direction and at equal speeds to that of counter-shaft 30.

The counter-shaft 31 is restricted against 130

longitudinal movement by the abutment of the hubs of the miter-gears 72 and 73 with the bearings 28 and 29.

The shafts 68 and 69 are restricted against longitudinal movement by the abutment of the hubs of miter-gears 70 and 71 and collars 74 and 75 with the bearings 66 and 67.

The counter-shafts 30 and 31 and miter-gears 62, 63, 72, and 73 thereon have the same direction of rotation. The miter-gear 60 meshes with the upper side of miter-gear 62 and the miter-gear 61 with the lower side of miter-gear 63, thereby rotating shafts 58 and 59 in the same direction. The miter-gear 70 meshes with the upper side of miter-gear 72 and the miter-gear 71 with the lower side of miter-gear 73, thereby rotating shafts 68 and 69 in the same direction. However, it will be seen that this construction causes the pair of shafts 58 and 59 to rotate in opposite directions toward the stock-guide 10 and in the direction of the projected feed along the same.

Upon the upper ends of the shafts 58, 59, 68, and 69 are respectively set eccentrics 76, 77, 78, and 79, like in size, shape, and eccentricity.

The eccentrics 76, 77, 78, and 79 are set on the shafts 58, 59, 68, and 69 in planes lying parallel with and at equal distances from the counter-shafts operating said respective shafts.

We have seen that the shafts 58 and 59 are mounted to rotate synchronously. The eccentrics 76 and 77 are fixed on shafts 58 and 59 at the same angle to the plane of mounting of said shafts by keys 80, and therefore rotate synchronously. We have also seen that the shafts 68 and 69 are mounted to rotate synchronously. The eccentrics 78 and 79 are fixed on shafts 68 and 69 at the same angle to the plane of mounting of said shafts by keys 80, and therefore rotate synchronously.

Each of the eccentrics 76, 77, 78, and 79 is provided with a rectangular peripheral groove 84. Circular plates 85 of greater diameter than the shafts and securable to the end of the shafts by machine-screws 86 serve to retain the eccentrics on their shafts and the keys in their seats. A tool-carriage 87 is carried on eccentrics 76 and 77, and a tool-carriage 88 is carried on eccentrics 78 and 79. The tool-carriages 87 and 88 are each provided with tool-beds 89, having longitudinal T-slots 90 for the attachment of a tool-head 138 thereto and guide-recesses 91 and 92 at either end thereof.

Each of the recesses 91 and 92 is provided with a transverse guide 93 and retaining-plates 94, each having a corresponding transverse guide 95, said plates shaped to fit and be secured by screws 96 to said tool-carriage to complete the perimeters of said recesses.

Split strap-blocks 97 embrace the eccentrics in the grooves 84 and are supported upon said eccentrics by the walls of said grooves.

The strap-blocks 97 are provided with rectangular grooves in their opposite sides adapt-

ed to engage the transverse guides 93 and 95 on the tool-carriages 87 and 88 to support the tool-carriages. Adjusting set-screws 98 are provided on the tool-carriages bearing upon the strap-blocks 97 for maintaining the embrace of the eccentrics by the strap-blocks and also to permit of the lateral adjustment of the tool-carriage relative to the eccentrics.

It will be seen that each tool-carriage being mounted on two synchronously-rotating eccentrics lying in the same plane will be given a translational movement in a circuitous path, and it will be further seen that as the shafts carrying the two eccentrics lie in a plane parallel to the stock-guide the tool-carriage will at all times be parallel with the stock-guide.

It has been pointed out that the pair of shafts 58 and 59 and the pair of shafts 68 and 69 rotate toward the stock-guide 10 in the direction of the projected feed along the same, and it will therefore be clearly seen that the tool-carriages 87 and 88, carried by the said pairs, will be given a circuitous movement toward the stock-guide 10 in the direction of the projected feed along the same, while the parallelism existing between them and the stock-guide will not be destroyed.

It is intended that the tool-carriages shall approach the stock-guide 10 consecutively that they may not interfere and at constant intervals to secure a uniform movement, and as this periodicity would be destroyed by moving one of the counter-shaft carriages a greater distance on the slide-rails 16 to give its tool-carriage a greater angle than the other the studs 41 and 50 of gears 39 and 42 are removably mounted in the link 43, and one of the gears 39 or 42 is adapted to be removed from the train while the adjustment is taking place to be again inserted therein to maintain the desired periodicity of movement of the tool-carriages.

On the outer face of the upright A, at either side of the aperture therein, before referred to, two shafting-brackets C and D are rigidly secured by bolts 99, and on the outer face of the upright B, at either side of the aperture, hereinbefore referred to, two shafting-brackets E and F are similarly secured.

A shaft 100 is mounted in bearings 101 and 102 in the shafting-brackets C and D and carries and is driven by a miter-gear 103, meshing with a miter-gear 104 on the shaft 8 and driven at the same speed as shaft 8. A gear 105, fast on shaft 100, drives, through a gear 106, a shaft 107. The shaft 107 carries a feed-roll 108, having a peripheral groove 109, conforming in cross-section with that of the stock-guide 10. The highest point of the groove 109 lies directly in alignment with the stock-guide 10 to engage stock lying in and projecting from said stock-guide.

The feed-roll 108 rotates at half the speed of the shaft 8, and consequently one-fourth the speed of the shafts 58, 59, 68, and 69.

The active gripping periphery of the feed-roll 108 is to be made four times the length of the chord of the arc formed within the profile of the stock by the path of a single point in the cutting edge of the cutter. Motion is transmitted from a gear 110 on shaft 107, through an idle gear 111, to a gear 112 on a shaft 113, mounted in bearings 114 and 115 in the shafting-brackets C and D.

The shaft 113 carries a feed-roll 116 identical in size and form with roll 108 and rotates at the same speed and in the same direction as roll 108. The highest point of the groove 109 of feed-roll 116 lies in alinement with the like point of that of roll 108 and the stock-guide 10. Two presser-rolls 117 and 118, identical in size and form, having peripheries substantially conforming to the profile of the stock to be operated upon and having active gripping-peripheries of the same diameter as those of feed-rolls 108 and 116, are mounted in adjustable bearings 119 and 120 in shafting-brackets C and D.

The bearings 119 and 120 of presser-rolls 117 and 118 are provided with downwardly-pressing springs 121 and 122 and are adjusted to vary the pressure by adjusting-screws 123 and 124, working on spring-caps 125 and 126 and mounted in retainer-plates 127, removably secured to the brackets C and D.

The miter-gear 103 meshes with the miter-gear 104 to give the rolls 108 and 116 a movement at their gripping-points in the direction of the projected feed of the stock.

A stud 128 is mounted in the shafting-brackets E and carries a miter-gear 129, driven in the same direction as gear 103 by a miter-gear 130 on shaft 8.

It will be seen that the miter-gears 103 and 129 mesh with the miter-gears 104 and 130 on opposite sides of shaft 8, rotating miter-gears 103 and 129 in the same direction.

An ejector-roll mechanism identical with the feed mechanism described as mounted on shafting-brackets C and D is mounted on shafting-brackets E and F and driven from miter-gear 129 in the same direction. The elements of said ejector mechanism being identical with those of the feed mechanism already described have been given the same reference characters for the sake of brevity.

A rotary brush 131 is mounted on a spindle 132, mounted in a bearing 133 in a support 134, in turn secured to the shafting-brackets E and F. A sheave 135 is mounted on the spindle 132 and is driven by a belt 136 from a sheave 137 on shaft 8. The brush 131 serves to brush out the chips from the stock before it passes to the ejector-rolls on brackets E and F.

The shaft 8 is restricted from longitudinal movement by the hubs of gears 104 and 9 and sheave 137.

The tool-heads 138 are adapted to be clamped to the tool-beds 89 by bolts 139, the heads of

which bolts 139 engage in the T-slots 90, 65 mounted in said head.

Tool-shank recesses 140 in the lower edge of the tool-heads 138 accommodate the shanks 141 of the tools 142, which are rigidly secured in said recesses 140 by binding-screws 143. 70 The adjacent binding-screws 143 are disposed upon the tool-head 138 out of alinement with one another to admit of the application of a wrench thereto.

The shanks 141 of the tools 142 are made 75 long and thin to admit of a certain amount of spring or give, the reason for which will hereinafter appear.

The first sixteen tools at the left (see Fig. 6) are made shorter and are set in a higher 80 plane (see Fig. 7) than the second sixteen at the left and are designed to cut a preliminary chip, while the second series of sixteen cut a deeper or finishing chip.

The distance between the centers of the first 85 and second series of tools is equal to the length of the path of the tool-carriage, which is shown by the dotted circles 144 and 145, showing the path of a single point in the cutting edge of one tool 142. 90

The tool traverses the arc between the points a and c on dotted circle 144 in cutting the finishing-chip at the same time that the stock travels along the chord between said points. The speeds of the tool and stock are exactly 95 equivalent at the points a, b, and c on the dotted circle 145, and therefore the tool travels uniformly with the stock at these points; but between these points there is a slight discrepancy between the velocities of the tool 100 and stock, owing to the angularity of arc and chord, but any ill effects of which, however, is counteracted by the springing or giving of the thin tool-shank.

Tools of various forms are used for cutting 105 different designs of ornaments, and a separate tool-head is provided for each design in which the distance between the individual ornamental characters is different, in which cases the tool-shank recesses are disposed at various 110 distances apart.

The tools forming the first series make a series of rough incisions at the same time that the second series of tools make the finished cuts, and upon the next succeeding circuit of 115 the tool-carriage, the stock having been fed along in the meantime, the finishing series of tools exactly register with the rough cuts previously made and finish them simultaneously as the roughing-tools make the next succeeding 120 series of rough cuts.

The gear-trains operating the tool-carriage are set to bring one carriage to its cutting position a little before the other, so that the tool edges will never interfere, and the tool-heads 125 are so set upon the carriages that the series of roughing-tools of one will register with and cut out the chip incised by the roughing series

of the other and the same as to the finishing series of tools.

The inclination of the shafts carrying the eccentricities of the counter-shaft carriages 5 should be ascertained in building the machine with regard to the scope of angular adjustment of the tools desired.

When a stock of different profile is to be used, the presser-rolls, which are movable, 10 should be removed and others substantially conforming to the profile of the stock, but having the same active gripping periphery, substituted.

Larger eccentricities may be used to give the 15 tool-carriages a greater throw; but when this is done the feed and presser rolls should be proportionally changed.

The tool-beds can be constructed of greater length, and other series of tools—for instance, 20 for making additional rough cuts or superimposed ornamental cuts—may be added.

The power might be applied directly to shaft 8, if desired, the form given being merely designed to remove the power-pulley to a more 25 convenient position.

Having described my invention, I claim—

1. A machine for carving designs in stock during the longitudinal feed movement thereof, the same comprising in combination, opposed 30 incising-tools reciprocatory toward and away from each other in meeting paths, to thereby form different sides of the design, and means for carrying such tools with the stock during that portion of the working stroke of 35 each in which it is engaged in incising the stock.

2. A machine for carving designs in stock during the longitudinal feed movement thereof, the same comprising in combination, opposed 40 incising-tools reciprocatory toward and away from each other in paths meeting at an angle, to thereby form different sides of the design, and means for carrying such tools with the stock during that portion of the working stroke of 45 each in which it is engaged in incising the stock.

3. A machine for carving designs in stock during the longitudinal feed movement thereof, the same comprising in combination, a 50 stock-guide, a roughing-out and a finishing tool disposed longitudinally of such guide, and means for carrying said tools with the stock during that portion of the working stroke of each in which it is engaged in incising the stock.

55 4. A machine for carving designs in stock during the longitudinal feed movement thereof, the same comprising in combination, a stock-guide, a set of roughing-out and a set of 60 finishing tools disposed longitudinally of such guide and in different planes, and means for carrying said tools with the stock during that portion of the working stroke of each set in which the tools thereof are engaged in incising the stock.

65 5. A machine for carving designs in stock

during the longitudinal feed movement thereof, the same comprising in combination, a stock-guide, opposed sets of tools, each opposing set comprising a roughing-out and a finishing tool disposed longitudinally of such 70 guide and which tools are reciprocatory in meeting paths, one roughing-out tool toward and away from another roughing-out tool, and a finishing-tool toward and away from another finishing-tool, to thereby form different sides 75 of the design, and means for carrying said tools with the stock during that portion of the working stroke of each in which it is engaged in incising the stock.

6. A machine for carving designs in stock 80 during the longitudinal feed movement thereof, the same comprising in combination opposed incising-tools reciprocatory toward and away from each other in meeting paths, to thereby form different sides of the design, 85 means for somewhat delaying the advancing movement of one tool with reference to the advancing movement of the other, and means for carrying said tools with the stock during that portion of the working stroke of each in 90 which it is engaged in incising the stock.

7. In a machine for carving designs in stock during the longitudinal feed movement thereof, the combination with carving-tools moving in a circuit approaching, accompanying and receding from the moving stock, a stock-guide, a feed mechanism adjacent to each end of the guide, and a brush for removing the chips from the stock prior to its engagement with the feed mechanism at the rear. 100

8. The combination with a stock-guide and means for feeding the stock continuously, of a tool-carrier, means for moving the same to and fro along the stock and also transversely of the stock, two cutters one below the other 105 and spaced apart along said carrier a distance substantially equal to the distance traveled by the stock during the time intervening between two successive working strokes of the carrier whereby the second tool deepens the 110 incision made by the first, a coöperating tool-carrier, and means for enabling said coöperating tool-carrier to travel with the stock.

9. The combination with stock-guiding means, of means for feeding the stock continuously, a tool-carrier, means for moving the tool-carrier both to and fro longitudinally of said stock-guide and also toward and from the stock in such a manner that the movement of the stock substantially coincides with the longitudinal movement of the tool-carrier during the incising operation; and two sets of cutting-tools, one set projecting beyond the other and spaced apart upon said carrier a distance substantially equal to the distance traveled by 120 the stock during the time intervening between two successive working strokes of the carrier whereby the tools in the second set lengthen the incisions made by the tools in the first set. 125

10. The combination with stock-guiding 130

means, of means for feeding the stock continuously, a tool-carrier, means for moving the tool-carrier both to and fro longitudinally of said stock-guide and also toward and from the stock in such a manner that the movement of the stock substantially coincides with the movement of the tool-carrier during the incising operation, and a plurality of similar carving-tools mounted in line upon said tool-carrier in such relation as to produce by repeated incising movements uniformly-spaced incisions in the stock, a second plurality of carving-tools also mounted upon said carrier and projecting beyond and located below the other set, the distance between the sets along the carrier being substantially equal to the distance traveled by the stock during the time intervening between two successive working strokes of the carrier whereby the incisions made by the first plurality are deepened and lengthened, and two sets of coöperating carving-tools mounted to incise the stock in a different direction.

11. The combination with stock-guiding means, of means for feeding the stock continuously, a tool-carrier, means for moving the tool-carrier both to and fro longitudinally of said stock-guide and also toward and from the stock in such a manner that the movement of the stock substantially coincides with the longitudinal movement of the tool-carrier during the incising operation, a plurality of similar carving-tools mounted in line upon said tool-carrier in such relation as to produce by repeated incising movements uniformly-spaced incisions in the stock, a coöperating tool-carrier, a plurality of tools therein, means for causing said coöperating tool-carrier to move with the stock during the incising operation, and means for effecting angular adjustment of either tool-carrier.

12. The combination with a stock-guide and means for feeding the stock continuously, of a tool-carrier, a plurality of actuators positively connected by said tool-carrier, for effecting movement thereof both longitudinally of the stock and transversely thereof, a coöperative tool-carrier mounted for movement with the stock during the incising operation, and means for effecting angular adjustment of either tool-carrier.

13. The combination with a stock-guide and means for feeding the stock continuously, of a pair of separate shafts, a tool-carrier supported by its ends upon said shafts, eccentrics upon said shafts, said eccentrics being positively connected by said tool-carrier, means for rotating said shafts in unison, means for effecting angular adjustment of said shafts, tool-carrier and eccentrics, and a coöperative tool-carrier mounted for movement with the stock during the incising operation.

14. The combination with stock-feeding means and a stock-guide, of two tool-carriers,

means for guiding the same, two pairs of eccentrics, each pair being positively linked together by one of said tool-carriers, driving means connected to all of said eccentrics for rotating each pair thereof in unison, and means for effecting angular adjustment of either tool-carrier, together with its guiding means and eccentrics.

15. The combination with a stock-guide and means for feeding the stock continuously, of two tool-carriers, means for moving the same to and fro along the stock and also in different directions transversely of the stock, and means for effecting angular adjustment of one of the tool-carriers.

16. The combination with a stock-guide and means for feeding the stock continuously, of two tool-carriers, a plurality of actuators positively connected by each of said tool-carriers, for effecting movements thereof both longitudinally of the stock and transversely thereof, and means for effecting angular adjustment of one of said tool-carriers with its actuators.

17. In a carving-machine, the combination with a stock-guide, of a circuitously-translatable chisel or chisels angularly adjustable about said guide as a center.

18. In a carving-machine, the combination with a stock-guide, of one or more travelers carrying circuitously-translating chisels, said travelers being angularly adjustable about said guide as a center.

19. In a carving-machine, a plurality of chisels movable to effect a translation of their cutting edges in meeting circuitous paths lying in intersecting planes, the positions of said cutting edges of said chisels coinciding at the point of meeting of said paths.

20. In a carving-machine, the combination with a frame having a stationary stock-guide and a driving-shaft, of one or more carriages angularly adjustable about said guide as a center, one or more chisels and mechanism for translating said chisels in a circuitous path carried by each of said carriages and extensible power-transmitting mechanism or mechanisms intermediate said driving-shaft and said mechanism.

21. In a carving-machine, the combination with a frame having a stationary stock-guide and a driving-shaft of one or more carriages angularly adjustable about said guide as a center, one or more chisels and mechanism for translating said chisels in circuitous paths, carried by said carriages or each of said carriages and a linked gear train or trains intermediate said driving-shaft and said mechanisms.

22. In a carving-machine, the combination with the frame and main power-shaft thereon, of a counter-shaft carriage adjustably mounted upon said frame, a counter-shaft journaled in said carriage, one or more chisels carried by said carriage and translated in a circuitous path from said counter-shaft, and a linked

gear-train forming extensible transmitting means between said power and counter shafts.

23. In a carving-machine, the combination with the frame and main power-shaft thereon, 5 of a counter-shaft carriage adjustably mounted upon said frame, a counter-shaft journaled in said carriage, one or more chisels carried by said carriage and translated in a circuitous path from said counter-shaft, and extensible power 10 transmission between said power and counter shafts.

24. In a carving-machine, the combination of a frame, a stock-guide thereon, counter-shaft carriages angularly adjustable about said 15 stock-guide as a center, chisels carried by said counter-shaft carriages and translatable from said counter-shaft, a power-shaft mounted on said frame eccentric to the path of adjustment of said carriages, and linked gear-trains form-

ing extensible power-transmitting means between said power and counter shafts. 20

25. In a carving-machine, the combination with a tool-carriage translationally movable in a circuitous path of a number of series of tools mounted thereon, the tools of each series protruding beyond and set in a lower plane than the preceding series. 25

26. In a carving-machine, the combination of a tool-carriage translationally movable in a circuitous path, of a number of series of tools mounted thereon, the distance between the centers of said series being equal to the length of 30 said circuitous path.

BENJAMIN W. TUCKER.
